OTHER PUBLICATIONS

An Office Action mailed by the United States Patent and Trademark Office on Sep. 5, 2019, which corresponds to U.S. Appl. No. 29/589,123 and is related to U.S. Appl. No. 29/691,012.

Primary Examiner — Steven J Czyz(74) *Attorney, Agent, or Firm* — Studebaker & Brackett PC

(57)

CLAIM

The ornamental design for a portable manual pulse generator as shown and described.

DESCRIPTION

FIG. 1 is a perspective view of my new design for a portable manual pulse generator showing my new design;

FIG. 2 is a front view thereof;

FIG. 3 is a rear view thereof;

FIG. 4 is a top plan view thereof;

FIG. 5 is a bottom view thereof;

FIG. 6 is a right side view thereof; and

FIG. 7 is a left side view thereof.

The broken lines shown in the figures illustrate portions of the portable manual pulse generator and form no part of the claimed design.
